CLAIM

The ornamental design for an exercise and fitness device with extended sleeve and carabineer, as shown and described.

DESCRIPTION

FIG. 1 is a front perspective view of an exercise and fitness device with extended sleeve and carabineer of the present invention showing my new design;

FIG. 2 is a front elevational view thereof;

FIG. 3 is a back elevational view thereof;

FIG. 4 is a side elevational view thereof;

FIG. 5 is an opposite side elevational view thereof;

FIG. 6 is a top plan view thereof; and,

FIG. 7 is a bottom plan view thereof.

It is understood that the broken lines within the surface of the claimed design indicate stitch lines which forms part of the claimed design.
